LOUIS ANGELUS, OF NEW YORK, N. Y.

PLAITING MACHINE

Application filed March 23, 1929. Serial No. 349,509.

My present invention relates generally to plaiting machines, and has particular reference to that type of machine wherein goods are preliminarily treated prior to final steaming subjection or the like.

For the purpose of explaining the nature of my present invention, I have herein illustrated and shall hereinafter describe the same as applied to a machine which is designed to sandwich a piece of goods to be plaited between two layers of paper or the like and to impart a so-called plaited configuration to the sandwiched assembly. In a machine of this character, a pair of reciprocating members or knives are adapted to grip the three-ply assembly in an intermittent manner and at successive portions thereof to force the same forwardly and thereby form a loop, the assembly thereafter passing between a pair of rollers which serve to crease the paper layers and thereby impart a temporary configuration to the goods. In combination with the foregoing, means are provided for guiding a supply of sheet material into proper association with two layers of paper and thence toward the reciprocating knives.

Where plaiting is accomplished in the foregoing manner, the purpose of the paper layers is to retain the fabric between them in the contemplated creased form for at least a temporary period of time during which the creased assembly may be suitably rolled and subjected to a final steaming operation. In order to facilitate the temporary retention of the properly formed creases, it has been customary to heat one of the rollers mentioned, as for example, by means of steam.

I have found that certain materials of tough or hard texture, such as rayon, for example, do not lend themselves readily to the preliminary creasing above mentioned. It is one object of my present invention to provide a plaiting machine whereby the initial creasing of such relatively hard fabrics is facilitated.

It is also well known that other types of fabrics, such as the relatively soft and pliable silks and chiffons, do not require the same amount of ultimate steaming for the

purpose of producing commercially satisfactory results. Another object of my invention is to provide a machine whereby such soft materials may, if desired, be completely treated without necessitating the usual ultimate subjection to steam treatment.

Briefly, my invention resides in the provision of a pre-steaming arrangement, whereby the goods to be plaited is efficiently and controllably subjected to the softening action of steam prior to the time that it is initially creased by the reciprocating members mentioned.

Inasmuch as many types of material become objectionably discolored under the action of water, and particularly where they are subjected to uneven or irregular amounts of water, it is an object of my invention to provide means for subjecting the goods to the pre-steaming operation without danger of spotting or discoloring the material by irregular application of steam or by condensation thereof.

It is a general object to provide a device which is extremely simple in construction and hence inexpensive from a manufacturing standpoint, the construction being practically foolproof and being capable of uniformly satisfactory operation even by comparatively unskilled operators.

For the attainment of the foregoing objects and such other objects as may hereinafter appear or be pointed out, I have illustrated several forms of my invention in the accompanying drawings wherein—

Figure 1 is a diagrammatic elevational view of a plaiting machine with which my present invention has been associated;

Figure 2 is a cross-sectional view through my improved pre-steaming device, the center portion having been broken away for lack of space;

Figure 3 is a cross-sectional view taken substantially along the line 3—3 of Figure 2;

Figure 4 is a fragmentary inverted plan view on a reduced scale of a modification; and

Figure 5 is a view similar to Figure 4 showing a second modification.

In the plaiting machine chosen for illus-

tration the supply of sheet material to be plaited is illustratively positioned in a box or container 10 from which it is led upwardly as at 11 over a work table 12, usually of wood or the like. A suitable guide roller 13 may be provided on the forward edge of the table 12. A supply of paper 14 is suitably mounted on a spindle 15 or the like whereby a layer or web of paper 16 may be drawn upwardly as illustrated. A similar 10 second supply of paper 17 is mounted in a similar manner upon the spindle 18 or the like to enable the drawing off of a web or layer 19.

15 The three layers 16, 11, and 19 are suitably brought into superposed relationship beneath the guide roller 20, the material to be plaited being sandwiched between the paper layers. From the roller 20 the three-ply assembly is 20 guided toward a pair of superposed rollers 21 and 22, these rollers operating intermittently in the direction of the arrows. A short distance in advance of the rollers 21 and 22, a pair of reciprocating knives or members 23 and 24 are provided, these members being 25 shown in Figure 1 at the extreme left end of their travel. At this point, they are automatically closed to grip the three plies between them and they are thereupon advanced toward the right to form a loop of material 30 on the left side of the rollers 21 and 22. As the latter then rotate by a slight degree to grasp and advance the looped portion between them, the knives 23 and 24 open to release the loop and travel back to the position 35 illustrated in Figure 1. As a result of the foregoing operation, automatically effected in a step by step manner, the three-ply assembly assumes a plaited configuration as 40 shown at 25, this preliminarily creased assembly being guided downwardly and received upon a table or the like 26. At the lower end of the latter it may be conveniently rolled up as at 27 whence it is ultimately taken in compactly rolled form for 45 subjection to a final steaming operation.

To facilitate the guidance of the creased assembly 25 on its way to the table 26, it is customary to provide a belt 28 extending 50 around the roller 21 and held downwardly upon the assembly 25 by means of a weighted roller 29 loosely received in the free loop of the belt 28.

55 Although the paper by its nature readily partakes of any crease that may be imparted thereto, it is advantageous to heat the roller 22 as by means of steam supplied from a conduit 30 and a pipe 31.

In accordance with my present invention, 60 I provide means for pre-steaming the goods 11 prior to its subjection to the creasing or plaiting operation of the members 23 and 24 and the rollers 21 and 22. I accomplish this by providing a steam table designated by the 65 reference numeral 32 in Figure 1 and pref-

erably positioned between the work table 12 and the guide roller 20. The paper web 16 is brought upwardly around the left end of the table 32, as indicated, whereby it is caused to underlie the sheet 11 as the latter passes 70 over the table 32. The steam employed by the table 32 may advantageously be supplied by a pipe 33 leading from the conduit 30 and provided with a control valve 34.

In Figures 2 and 3 I have illustrated the 75 features of the table 32. It consists essentially of a top surface over which the sheet 11 passes, of a chamber suitably arranged beneath such top surface, of means for supplying steam to such chamber and ejecting it 80 upwardly through the sheet passing thereover, and means for retaining the entire top surface in a constantly heated condition to prevent any condensation thereon.

85 In the construction which I prefer to employ, whereby the contemplated advantages of my invention are satisfactorily carried out, I provide a sheet-metal top portion 35 of substantially inverted-U cross-section, most clearly shown in Figure 3. A complementary bottom portion 36 is provided which is of substantially upright-U cross-section, the upwardly disposed arms 37 of the portion 36 being designed to nest with the downwardly 90 extending sides 38 of the top portion 35. In 95 this way, a chamber is provided which is co-extensive in length with the top surface of the portion 35, measuring length in the direction of travel of the sheet 11.

100 At its midportion, the bottom 36 is provided with a V-shaped trough or channel 39 whose depth is preferably made to vary as shown in Figure 2.

105 The portion 36, although coextensive with the portion 35 in length, as this term has been defined above, is not coextensive in the lateral direction with the portion 35, for a purpose presently to be described. Accordingly, a sheet-metal end plate 40 is provided to seal the left end of a chamber referred to (as viewed in Figure 2), and a similar sheet-metal end plate 41 is provided with the opposite side.

110 The pipe 33 is brought into association with the foregoing device by means of an elbow 42 from which a pipe 43 extends through the end wall 40 and across the entire device as shown in Figure 2. The pipe 43 is positioned within the channel 39 as shown in Figure 3, and is provided with a dead end 44. 115 Furthermore, the pipe 43 is provided with apertures 45 on its lower portion, whereby steam may pass outwardly through the apertures 45 and into the chamber defined by the portions 35 and 36. Any condensed moisture 120 in the steam will pass along the notch of the channel 39 and will ultimately be led off through a suitable drain 46 arranged at the lowest end of the channel. The drain 46 is provided with no valve whatsoever so that 125

there may be no possibility of any accidental sealing of the chamber.

Along its midportion, and preferably above the channel 39, the top surface of the portion 35 is provided with a series of openings or apertures 47. Steam will emerge from these apertures and will thus be caused to pass through the sheet 11 during the passage of the latter over the table 32. By properly controlling the valve 34, the amount of steam thus entering and pre-steaming the sheet 11 may be controlled. At the same time, it is to be noted that the entire chamber beneath the top wall of the table is constantly filled with steam and that the top surface is thereby continuously retained in a heated condition. This precludes any possibility of condensation upon the exterior surface, the collection of which in pools of water or otherwise would cause discoloration and other serious impairment of the material 11, not to speak of the annoyance and sloppiness which would be entailed. The chamber in this way constitutes not only a reservoir for the steam actually to be employed in pre-steaming the material, but serves the additional function of heating the top surface over which the material is passing; and I consider this an important feature of my present invention because of the danger, in the absence of such provision, of damaging the material and rendering the machine unsatisfactorily usable, as outlined above.

This feature of my invention is carried out to a further extent in connection with the mounting of the table as a whole. This mounting is accomplished as illustrated most clearly in Figure 2 and involves the shortening of the bottom portion 36 as previously referred to. Beneath the extreme lateral ends of the top portion 35 I provide blocks or castings 48 of metal or other material capable of conducting heat. These blocks are preferably enclosed in sheet-metal by means of the elements 49, although such enclosure is not essential; and suitable bolts or studs 50 are caused to pass downwardly through the blocks 48 and into association with suitable brackets 51 provided on the framework of the machine. The continuous presence of steam in the main chamber beneath the top surface of the table serves to heat not only the top surface in direct contact with the steam, but also the end plates 40 and 41, and by means of conduction the extreme lateral ends of the top portion 35 are maintained at a degree of heat sufficient to prevent any condensation thereon. The metallic blocks 48 serve not only to facilitate the mounting of the table but also to maintain the upper surface in conductive relationship with the heated chamber.

In order to control the quality of the steam leaving the chamber from the openings 47, it may in certain cases be desirable to recon-

struct the pipe 43 with a looped construction of the character illustrated in Figure 4. In this form, a pipe 52 enters the chamber and is then doubled back upon itself to provide the three lengths 53, 54, and 55. A dead end 56 is provided as before, but only the length 55 is perforated as shown at 45 in Figure 3. As a result of this construction, the steam freely occupying the chamber is subjected to additional heat emanating from the lengths 53 and 54, and a normally moist steam may in this way be rendered satisfactory for causing an egress from the top surface of the table of a comparatively dry steam.

In Figure 5, I have illustrated a further modification wherein the quality or relative dryness of the steam may be controlled and altered from time to time as conditions may require. In this embodiment, a pipe 57 is provided of a single length as shown in Figures 2 and 3; and an entirely independent loop or coil 58 having an inlet at 59 and an outlet at 60 is caused to pass into and out of the chamber so as to provide the additional heat to the steam occupying the chamber. A suitable valve or valves (not shown) may be manipulated to control the amount of steam passing through the coil 58, and the amount of such steam may be altered to vary and control the particular quality or relative dryness of the steam emanating from the length 57.

A machine constructed in accordance with my invention is highly satisfactory for treatment with all types of materials, including the relatively stiff or hard materials such as rayon. The pre-steaming of the material renders it more easily susceptible to the action of the members 23 and 24 and the rollers 21 and 22. A machine of this character is also capable of commercially plaiting soft materials, such as silks or chiffons, without any necessity for subjecting the same thereafter to further steaming treatment. I have found that the pre-steaming effected by the table 32 is sufficient in the case of relatively soft materials to produce a commercially complete result at the roll 27 of Figure 1.

In general, it will be obvious that the machine facilities the plaiting of materials, regardless of their character, that it is easily operated, reliable, and devoid of such faulty design or omission of essential parts as might otherwise cause a step of pre-steaming to have injurious effects upon the material.

In general, it will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and il-

lustrated its use, what I claim as new and desire to secure by Letters Patent is—

1. In a pre-steaming plaiting machine, a plaiting device, means for guiding a sheet of material to be plaited toward said device and including a steam table over which said sheet passes, said table comprising a sheet-metal top portion of inverted-U cross-section, and a complementary sheet-metal bottom portion of upright-U cross-section; a V-shaped channel in said bottom portion, and a conduit in said channel having downwardly directed apertures; whereby steam supplied to said conduit will pass from said apertures into the chamber defined by said portions, and whereby the top surface of said top portion will be heated thereby.
2. In a pre-steaming plaiting machine, a plaiting device, means for guiding a sheet of material to be plaited toward said device and including a steam table over which said sheet passes, said table comprising a sheet-metal top portion of inverted-U cross-section, a complementary sheet-metal bottom portion of upright-U cross-section, said portions defining a chamber for the reception of steam, said bottom portion being shorter in lateral length than said top portion, and fastening blocks of heat-conductive material associated with the lateral ends of said top portion; whereby the entire exposed upper surface of said table may be retained in heated condition to prevent condensation thereon.

In witness whereof I have signed this specification this 14 day of March, 1929.

LOUIS ANGELUS.
